UNITED STATES PATENT OFFICE.

VIRGINIUS Z. CARACRISTI, OF ALBANY, NEW YORK, ASSIGNOR TO LOCOMOTIVE
PULVERIZED FUEL COMPANY, A CORPORATION OF DELAWARE.

SYSTEM FOR FEEDING PULVERIZED FUEL.

1,214,753.

Specification of Letters Patent.

Patented Feb. 6, 1917.

Application filed October 4, 1913. Serial No. 793,311.

To all whom it may concern:

Be it known that I, VIRGINIUS Z. CARACRISTI, a citizen of the United States of America, and resident of Albany, in the county of Albany and State of New York, have invented certain new and useful Improvements in Systems for Feeding Pulverized Fuel, of which the following is a specification.

10 This invention relates to fuel-feeding systems, and has for its object to provide an improved means for feeding fuel from a receptacle, which fuel is mixed with a proper amount of oxygen, preferably by the action 15 of an air-blast, the proportion of fuel being capable of regulation to suit the various requirements, and so arranged that any excess of fuel over that mixed with the oxygen is returned to the receptacle.

20 For this purpose my invention consists of the following novel features and combinations of parts which will be fully described hereinafter and finally set forth in the claims.

25 In the accompanying drawings, which show an embodiment of my invention, Figure 1 is a vertical longitudinal cross-section of my improved device used to carry out my invention, and Fig. 2 is a vertical 30 transverse section taken on line 2—2 of Fig. 1.

Similar reference characters indicate corresponding parts throughout the views.

Referring to the drawings, the casing 10 is 35 supported by a standard 11 arranged to give equilibrium to the casing. The front part of the casing 10 is provided with a converging member 13 adapted to receive the fuel and air intimately mixed and convey this 40 mixture to the furnace where the fuel is brought to the ignition point. The casing 10 is provided with an opening 17 in which is seated a member 14, having vanes or blades 15 arranged in helical screw-fashion.

45 The forward end of this member 14 is provided with openings 16 which bring about the communication of the interior of the member 14 with the interior of the casing 10 so as to enable any air that is forced into the pipe 12, and from there into the casing 10, to enter the openings 16 and pass from the exterior to the interior of the member 14. From thence the air follows the direction of the arrows indicated by 30. Within the

member 14 and within the spaces left between the innermost ends of the blades 15, a second member 20 is arranged, which has within it a screw 21 intended to feed the fuel, in the direction of the arrow 31, from the member 20 into the forward end of the member 14, so that the fuel, as it is fed forwardly, is impinged by the air entering the opening 16. The surfaces of the veins 15 adjacent the periphery of the internal screw member 20 can be so shaped that they act as bearing surfaces to permit the revolution 65 of this internal member 20. When this impingement takes place a very intimate contact between the oxygen and fuel takes place so that the mixture is ready for combustion, 70 and the fuel fed forwardly by the helical screw 21, in the direction of the arrow 31, is forced into the member 13 in intimately mixed condition, and from thence into the furnace, to be there burned. Whatever 75 fuel is not taken up by the air, drops to the lowermost portion of the member 14 and is caught up by the vanes or blades 15 and returned to the rearward portion of the member 14 and exterior of the member 20, until 80 it is dumped into some suitable container, in the direction indicated by the arrow 33.

When the screw 21 rotates, fuel is discharged in a loose powdery condition in a parabolic and downward stream into the 85 forward end of the member 14, and this effect may be further increased by further breaking up the fuel by any suitable means if desired, so that the fuel is fed into the forward end of the member 14 in a finely-divided condition. On entering the forward part of the member 14 the fuel is subjected, as before stated, to the action of an air-blast entering through the orifices 16. These orifices are preferably inclined to the mouth 90 of the sleeve, so that the blast will carry the pulverized fuel away in the direction of the arrows 30. These orifices are also preferably open between threadings of the screw or similar inclined surfaces, which may be 95 revolved, so that the air-blast has circular eddies and whirls, whereby the stream of fuel is thoroughly broken up and mixed with the air. Some of the orifices preferably communicate with the interior of the blades 100 15, so that the returning fuel is again subjected to the air-blast.

The feeding devices may be of any equiv-

alent form, and the blast may be produced by the furnace or any other suitable mechanical device. The member 14 may be rotatably mounted in any suitable manner as known to those skilled in the art. So also, suitable means may rotate the inner screw 21. In the drawing, the second member 20 is shown so as to be capable of being arranged to rotate with either screw or stay still.

10 I have described an embodiment of my invention, but changes may be made therein without departing from the spirit of my invention as defined by the appended claims.

15 What I claim and desire to secure by Letters Patent is:

1. In a burner for pulverized fuel, comprising feeding means for feeding fuel, return means concentric with said feeding means and extending beyond the point 20 where the fuel is discharged from said feeding means in the direction of feed for returning portions of the fed fuel, and air feeding means at the discharge end of said fuel feeding means for feeding air to said fuel as it leaves the fuel feeding means and as it commences its return movement in the return fuel means, said air feeding means 25 concentrically surrounding the discharge end of the fuel feeding means and directing 30 the stream circumferentially against all sides of the fuel as it leaves the fuel feeding means, said air feeding means being located intermediate the point where the fuel is fed from said feeding means, and the 35 point where it is returned by said return means.

2. In a burner for pulverized fuel, an inclosed mixing space connected therewith, means for feeding a current of fuel, means 40 for injecting inclined currents of air into said mixing space underneath said current of fuel and beyond the end of the fuel feeding means, and means around said fuel feeding means for returning the fuel not swept along by the air current to its original receptacle.

3. In a burner for pulverized fuel, an inclosed space for mixing air and fuel, means 50 for injecting currents of fuel and air therein, moving surfaces, and means for impinging the air current upon moving said surfaces in the direction of the fuel flow before it impinges upon the current of fuel.

55 4. In a burner for pulverized fuel, an inclosed space for mixing said fuel with air, air feeding means for feeding the current of air to said inclosed space, and concentric feed and return screws operating in opposite 60 directions to respectively feed the fuel against the air current and to return the fuel not swept along by said air current to its original receptacle, the said return screw extending beyond the said feed screw in the 65 direction in which the fuel is fed from said

feed screw, the said air feeding means being located intermediate the discharge end of the feed screw from which the fuel is fed, and the adjacent end of the return screw.

70 5. In a burner for pulverized fuel, an inclosed space for mixing air and fuel, means for feeding a current of fuel therein, means for injecting a current of air therein, against said current of fuel, and means for returning the fuel not swept along by said air current to its original receptacle, said air current being admitted in the return path of the fuel to its original receptacle.

75 6. In a burner for pulverized fuel, an inclosed space for mixing said fuel, a screw for feeding a current of fuel therein, means for injecting a current of air therein, against said current of fuel, and a screw for returning the fuel not swept along at first by said 80 air current to its original receptacle, said air current being admitted between the vanes of said returning screw.

85 7. In a burner for pulverized fuel, a mixing member for air and fuel, a feed screw for feeding a stream of fuel thereto, a second feed screw around the first feed screw for returning the fuel dropped therein to its original place, and a plurality of individual air conduits circumferentially 90 arranged in respect to the first feed screw for impinging air currents against the fuel fed by the first feed screw, as it emanates therefrom, and for impinging the air currents against that portion of the fuel as it 95 is taken up by the second feed screw for the purpose of mixing air with the fuel thereby carried.

100 8. In a burner for pulverized fuel, a mixing member for air and fuel, an air feeding member arranged around the mixing member, a fuel and air feeding member, having converging walls arranged in front of the air feeding member, and a member at the rear of the air feeding member comprising 110 a feed screw, a plurality of air conduits circumferentially arranged at that portion of the feed screw where it enters the air feeding member, whereby communication is made between the air feeding member and 115 the mixing member, and a second feed screw of reverse inclination within the first main feed screw and having its end free of the air conduits, and at one end of the mixing member, so that any fuel fed thereby is impinged by the air currents passing through the air conduits into the mixing member.

120 9. In a burner for pulverized fuel, a mixing chamber for air and fuel, means for feeding a stream of fuel into said chamber, 125 means for directing an air current against said stream of fuel, means for again carrying those portions of the fuel not originally swept away by said air current directly into the path of said air current in said mixing 130

chamber, and means for returning those portions of the fuel not swept away to the original receptacle therefor.

10. In a burner for pulverized fuel, a mixing chamber for mixing said air and fuel, means for feeding a stream of fuel into said chamber, independent means for impinging in the direction of the flow of the stream of fuel, a current of air circumferentially against all sides of said stream of fuel, as it is fed into the mixing chamber and beyond the end of the fuel feeding means, and means circumferentially around the fuel feeding means for again directly carrying those portions of said fuel not originally passing into said mixing chamber, to the fuel feeding means to be again fed to the mixing chamber and there subjected to the operation of the current of air.
20. 11. In a burner for pulverized fuel, comprising means for feeding fuel, means for returning a portion of the fuel, concentrically surrounding said feeding means, and extending beyond the discharge end thereof, and means at the discharge end of said fuel feeding means for feeding a plurality of

separated streams of air to said fuel as it leaves the fuel feeding means, and as it commences its return movement in the return fuel means, said means concentrically surrounding the discharge end of the fuel feeding means and directing the stream circumferentially against all sides of the fuel as it leaves the fuel feeding means, the said means for feeding the air being located intermediate the point where the fuel is fed, and the point where it is returned.

12. In a burner for pulverized fuel, an enclosed space for mixing air and fuel, means for injecting a current of air and fuel therein, moving surfaces at the end of said fuel and air feeding means, and means for impinging a current of air upon said moving surfaces before mixing it with said fuel in the direction of the fuel flow.

In testimony that I claim the foregoing as my invention, I have signed my name in presence of two subscribing witnesses.

VIRGINIUS Z. CARACRISTI.
